UNITED STATES PATENT OFFICE.

JOHN CLETIOUS EPLER, OF PHILADELPHIA, PENNSYLVANIA.

GARMENT-HANGER AND LOCK.

No. 844,305.

Specification of Letters Patent.

Patented Feb. 12, 1907.

Application filed May 5, 1906. Serial No. 315,440.

To all whom it may concern:

Be it known that I, JOHN CLETIOUS EPLER, a citizen of the United States, and a resident of Philadelphia, in the county of Philadelphia and State of Pennsylvania, have invented 5 a new and Improved Garment-Hanger and Lock, of which the following is a full, clear, and exact description.

The purpose of the invention is to provide 10 a hook adapted to receive a coat or like garment and a hat, together with a chain or its equivalent, whereby to hang a bag, and also a clamping device for umbrellas and canes and means for locking the wearing-apparel 15 and an umbrella or cane in their supports, which means are simultaneously operated to lock or to release the articles by the action of a single, preferably key-controlled, lock.

A further purpose of the invention is to so 20 construct the lock and key that when the receivers for the articles are unlocked the key cannot be withdrawn and to so construct the device that it can be placed in any desired position and attached to any desired object 25 and so that the device will be simple, durable, reliable, and economic.

The invention consists in the novel construction and combination of the several parts, as will be hereinafter fully set forth, 30 and pointed out in the claims.

Reference is to be had to the accompanying drawings, forming a part of this specification, in which similar characters of reference indicate corresponding parts in all the figures.

Figure 1 is a front elevation of the device. Fig. 2 is a sectional side elevation. Fig. 3 is an enlarged bottom plan view of the device with the cover removed and showing the operative parts in position to lock the receivers for the several articles. Fig. 4 is a view similar to Fig. 5, but showing the operative parts in the position they occupy when the receivers are unlocked for the removal of articles. Fig. 5 is an enlarged transverse section through a portion of the casing, a plan view of a portion of the locking device for the garment-hook, and a sectional plan view of a lock for the same. Fig. 6 is also an enlarged 45 transverse section through a portion of the casing and a sectional plan view of the clamping device or receiver for canes or umbrellas. Fig. 7 is a detail sectional view through a portion of the casing and the lock,

showing the key in side elevation in the lock; 55 and Fig. 8 is an outer face view of a portion of the casing and the keyhole-cylinder, illustrating the manner in which the key is locked in the casing when the tumblers are in position to provide for the unlocking of the receivers.

A represents a casing which may be of any desired shape or size. In the drawings the casing is shown as rectangular and is provided with a removable bottom plate 10, 65 held spaced a suitable distance from the front of the casing by lugs 11, as shown in Figs. 3 and 4, and lugs 12 are formed upon the inner face of the front of the casing, extending to an engagement with the inner 70 face of the bottom plate 10. These lugs are adapted to receive screws whereby to hold the cover or back plate 10 in place.

A garment-hook B is secured to the front outer portion of the casing A in any suitable 75 or approved manner, usually by screws 14, as is shown in Fig. 2. This garment or wardrobe hook is provided with a bifurcated body, as shown in Fig. 2, and its outer end portion is upwardly curved, as is illustrated in both 80 Figs. 1 and 2. In the upper edge of the body of the said hook B a recess 15 is preferably made.

An elongated link 16 is adapted to be slid over the garment-hook B upon its body to 85 the recess 15 therein, and prior to placing the garment-hook B in position a ring 17 is slipped upon the lower member of said hook, so that when the hook is in position this ring 17 cannot be removed therefrom.

One end of a chain C is secured to the ring 17, and the said chain between its ends is secured to the link 16. Under this arrangement a loop-section a is formed and a pendant end section a', which latter section is 95 provided at its free end with an attached ring 18 of sufficient size to slip over the outer end portion of the said garment-hook. This garment-hook is adapted to support a coat or a like garment, the strap at the back of the 100 neck being passed over the said hook, and a hat is adapted to rest upon the outer end of the hook B in the customary manner. Should a bag also need to be cared for, the link 16 is slipped from the garment-hook B 105 and is passed through the bail or handle of the bag, and then said link is slipped to position on the garment-hook.

In connection with the garment-hook B a locking-arm D is employed, located above the hook. This locking-arm is curved downward in direction of the outer end of the garment-hook B, approaching the latter sufficiently close to just admit a hat of ordinary thickness being supported between the two points without injury to the material of the hat. This locking-arm D is pivotally mounted in the casing and is adapted to have a quarter-revolution, so that it can move sufficiently from the garment-hook B to permit the introduction of a hat, for example, on the garment-hook or for the ready removal of articles therefrom. To that end a stud 19 is formed at the inner end of the base portion of the locking-arm D, as is shown in Fig. 5, which stud is loosely passed through a suitable opening in the casing A. The inner end portion of this stud 19 is made polygonal and is passed into a correspondingly-shaped opening in a disk 20, located within the casing, as is also best shown in Fig. 5, the disk being locked to the stud 18 by a suitable nut 21, so that when the disk 20 is turned the locking-arm D is turned also and to the same extent. This disk 20 is provided with a recess, preferably a rectangular recess 22, in its periphery, as shown in Figs. 3 and 4, and with a peripheral groove 23, leading from and connecting with the recess 22, the said groove extending along the periphery of the said disk about a quarter of its circumference, as is shown by dotted lines in Figs. 3 and 4. The said groove 23 is of even depth throughout. A spring 24 is located above and is in peripheral engagement with the disk 20, the upper end of the spring being secured to a stud 25, located above and at one side of the disk, and the other end of the disk 24 is secured, by means of a screw 26 or its equivalent, to the periphery of the disk adjacent to the recess 22, but at the side opposite that at which the groove 23 is formed, as likewise shown in Figs. 3 and 4. This spring 24 is placed under tension when the disk 20 has been turned in direction to carry the locking-arm D to a position of closure relatively to the hook B, as is shown in Figs. 1 and 2, in which position the disk is locked by the locking devices to be hereinafter described. When the locking devices just referred to release the disk 20, the spring 24 acts to carry the locking-arm D to a releasing position or to a position removed from the hook B. When the hook is carried to its releasing position, it moves laterally from the hook and its point is given an upward turn.

The lock for the disk is of peculiar construction and is best illustrated in Figs. 3, 4, 5, 7, and 8. Above and beyond the inner peripheral portion of the disk 20 a cylindrical guard 27 for the key D' is mounted to turn in the front member of the casing, extending within the chamber of said casing a required

distance. This guard-cylinder for the key is provided with a slot 28, extending through from end to end for the passage of the key when the said slot 28 is brought into registry with a slot 29, produced in the front member 70 of the casing and connecting with the opening in which the key-guard 27 is mounted to turn.

Three tumblers 30, 31, and 32 are employed, laid loosely one upon the other, and these tumblers are located just below the key-guard 27, and each tumbler is provided with a corresponding slot 33 at its inner end portion, through which slots a pin or stud 34 is passed, whereby to support the inner 80 end portions of the said tumblers and permit them to have sliding motion to and from the disk 20, since the outer ends of the tumblers 30, 31, and 32 are adapted to enter the recess 22 in the said disk 20 when the disk is turned 85 to expand a spring 24, and this is accomplished by moving the locking-arm D from its open to its closed position.

Each tumbler is provided with an attached spring 35, and said springs extend downward 90 from the tumblers and are made to engage with a common stud 36, extending inward from the front member of the casing, as is shown in Figs. 2, 3, and 4, the springs 35 having such bearing on the stud 36 as to normally force the tumblers in direction for engagement with the disk 20. Each disk is provided with a slot 37 in its upper edge, and these slots 37 in the outer tumblers 30 and 32 are in registry in both positions of the 100 tumblers, while the slot 37 in the intermediate tumbler 31, which is a stop-tumbler, is slightly to the rear of the slots in the tumblers 30 and 32, but partially in alignment with the slots in the latter tumblers, as clearly 105 shown in Fig. 5. When the disk is in position to receive the tumblers and the tumblers have entered the recess 22 in the disk, the slots 37 in the tumblers will be in alignment with the key-slot 29 in the outer member 110 of the casing.

Although the three tumblers are adapted to simultaneously enter the slot 22 in the disk 20 when the arm D is to be locked in its closed position, when the disk is released 115 from locking engagement with the said tumblers the central tumbler 31 travels in the peripheral groove 23 of the disk 20, while the outer tumblers 30 and 32 engage with the plain peripheral surface of the said disk at opposite sides of the said groove, as illustrated in Fig. 3. Therefore when the key is introduced into the slots of the tumblers for the purpose of throwing them from locking engagement with the recessed portion of the 125 disk the tumblers 30 and 32 will be given a far greater inward throw, or a throw away from the disk, than will be given the intermediate tumbler 31, and while the outer tumblers 30 and 32 are thus entirely removed 130

from the recess 22 the intermediate tumbler 31 is but partially removed, and consequently is opposite the groove 23 when the spring 24 acts to turn the disk 20 to its unlocked position, (shown in Fig. 4,) and at such time the intermediate tumbler 31 by striking the closed end of the groove 23, as is also shown in Fig. 4, limits the return movement of the said disk 20, preventing it from making more than a quarter of a turn, which is all that is sufficient to bring the locking-arm D sufficiently away from the garment-hook B.

The outer end portions of the tumblers move between guide-lugs 39, adapted to receive screws 41, and these screws 41 likewise secure a triangular guard-plate 40 to the inner tapped end portions of the said lugs 39, as is shown in Figs. 3 and 4, and the inner end of this guard-plate 40 is provided with an opening which receives the lower recessed portions 42 of the key-guard 27, as is shown in Fig. 7, and thus practically bridges the upper portion of the slot 37 in the uppermost tumbler 32, as is shown in Figs. 3, 4, and 7, and this is done in order to form a bearing for the inner end of the key D'. The said inner end of the key, as is shown in Fig. 7, is provided with a recess 43, which receives the bridge portion of the said guard-plate 40 just referred to, enabling one bit of the key to be in the outer end portion of the key-slot 28 and another bit to be within the slots 37 in the tumblers. Furthermore, at the handle portion of the key D' a deep recess 44 is made in one side edge, which recess is preferably deeper than the length of the keyhole-slot 29 in the casing, as is shown in Fig. 7. Therefore when the key is turned to the position shown by dotted lines in Fig. 8, which position it assumes when it has drawn the tumblers inward or out of locking engagement with the disk 20, the lower wall of the recessed portion 44 of the key will have been brought beneath the solid portion of the casing adjacent to the keyhole-slot 29, thus preventing the key from being withdrawn since the tumblers cannot be restored to locking contact with the disk 20 until the arm D has again been brought into locking position relatively to the garment-hook B.

The locking-arm D being in open position and the coat or other garments and bag, if desired, having been suspended from the garment-hook B, the hat of the wearer is finally placed upon the outer end of the said hook, and then the locking-arm D is closed, and the crown of the hat will be held between the opposing end surfaces of the arm D and the hook B.

In connection with the casing I have provided a clip or clamp E, which is adapted to receive the upright portion of an umbrella-handle or the body portion of a cane and is adapted to be locked, so as to prevent the

withdrawal of the object held, but so that the object may be released therefrom when desired by the proper individual. When this clamp or clip is associated with the garment-hook and its locking-arm, it is by preference placed to one side of the hook, as is shown in Fig. 1, and at the selected part of the casing A an opening 45 is made in the front member of the casing, as shown in Fig. 6, which opening receives the outer end portion of a box 46, the outer end portion 47 of which box is open. The said box is provided with lugs 48, which engage with the inner face of the front member of the casing and is secured thereto by screws 49 or like devices. In the back of the said box 46 longitudinal slots 50 are produced, one at each side of the center, as is also shown best in Fig. 6, and at the central portion of the back a boss 51 is produced, adapted to receive a screw 52.

Retaining-arms 53 and 54 are employed, which extend out beyond the front face of the casing, and these arms are reversely curved, so as to form practically a segmental space between them; but the outer ends 55 of the arms are brought sufficiently close together when the arms are in their retaining position to prevent the withdrawal of an object placed between them until the said arms are unlocked. The arms are pivoted at their inner ends by pivot-pins 56, which are passed through the box 46 adjacent to its open end, and at the outer sides of the pivots 56 an inwardly-extending lug 57 is preferably made integral with the base portion of each arm 53 and 54, as best shown in Fig. 6. The outer ends of the arms 53 and 54 are normally held quite close together by means of a spring 58, which is interposed between the lugs 57. Each lug 57 is provided with an inwardly-extending pin extension 59. These pin extensions project through the openings 50 in the back of the box 46.

A plate 60 is held to slide on the back of the box 46, and this plate is provided with a central substantially longitudinally elongated opening 61, through which the screw 52, above referred to, is loosely passed, so that the said plate while held in position on the box is free to slide thereon. The plate 60 is further provided with a horizontal opening 62 at each side of the central elongated opening 61, the opening 62 being in the same plane as the openings 50 in the box 46. Thus the retaining-arms 53 and 54 of the clamp E being in their normal position, if the plate 60 is slid outward, so as to bring the solid portion of the plate over the pin projections 59, as shown in Figs. 3 and 6, it will be impossible for the retaining-arms 53 and 54 to be separated; but if the said plate 60 is slid inward, so as to bring its opening 62 in registry with the openings 50 in the back of the box 46, as is shown in Fig. 4, the retaining-arms 53 and 54 may then be separated, since the pin projections 59 can

extend out and have movement in the openings 62, as well as in the openings 50, and at such time it is possible to remove an object from between the said retaining-arms. When 5 the clip or clamp E is associated with the hook B and locking-arm D, the plate 60 is provided with a shank 63, which is pivoted at its inner end to the disk 20 at one side, preferably the outer side, of the recess 22 therein, as is shown at 64 in Figs. 3 and 4. When this construction is employed, as the disk 20 moves to its unlocked position (shown in Fig. 4) it will draw the shank 63 inward, and consequently the connected plate 60, and when the disk 20 reaches its position of rest (shown in Fig. 4) the openings 62 in the plate will be over the openings 50 in the box 46. When the disk 20 is turned for locking engagement with the tumblers of the lock, as is 20 shown in Fig. 3, the shank 63 will be forced outward, and likewise the plate 60, and the solid portion of the plate will cover the slot- 50 in the box 46 and hold the retaining-arms in their retaining position against outside 25 pressure, as clearly illustrated in Fig. 6. I desire it, however, to be understood that the hook B and the locking-arm D and its connections, together with the lock, may be employed without association with the clamp or 30 clip E and also without having the chain attachment, if so desired.

It is also evident that the clamp or clip E may be used independently of the locking-arm D and the hook B, the disk 20 and connected parts, together with the lock, being retained, and means provided for turning the disk to locking position.

Above the clip or clamp E, I preferably place two stationary outwardly-extending 40 prongs 65, adapted to receive between them and support the handle of an umbrella or cane, and these prongs are generally passed through the front face of the casing A and are secured in position by nuts 66 screwed upon their inner edges.

The device may be made of any size, and any appropriate material may be employed in its construction.

Having thus described my invention, I 50 claim as new and desire to secure by Letters Patent—

1. In mechanisms for supporting and locking articles to their supports, a casing, a garment-support secured to said casing, a locking-arm pivotally mounted in the casing above the garment-support, the free end of the said arm being adapted in one position thereof to be over and in close proximity to the corresponding end of the garment-support, the said free end of the arm in its other position being removed from the vicinity of the said garment-support, a disk secured within the casing at the inner end of said locking-arm, which disk is provided with a 65 peripheral recess and with a peripheral

groove connecting with the recess, a spring having one end secured to the casing and the other end to the said disk at the side opposite that provided with the said groove, a key-operated bolt supported by the said casing, a series of spring-controlled tumblers arranged for simultaneous and bodily operation, all of said tumblers being adapted to enter the recess in the disk when the locking-arm is over the said garment-hanger when 70 said locking-arm is in releasing position, whereby one of said tumblers enters the groove in the said disk, acting as a stop therefor, the associated tumblers having frictional engagement only with the said disk. 80

2. In mechanisms for supporting and locking articles to their supports, a rigid supporting member, a revoluble locking member having a keeper-section and mounted for movement to a position over the support and in close proximity thereto and to a position removed from the support, a tension device for the locking member, controlling its movement to open position, a locking device for holding the locking member in position over the support, the said locking device being manually operated to said latter position, and a box-casing fitting in the main casing, open at the front and provided with openings at its rear, spring-controlled retaining-arms pivoted in 95 the said casing and having projections which extend into the openings at the back of the casing, a plate mounted to slide on the back of the casing, having openings therein capable of registry with the openings in the casing, and a connection between the locking-arm and the said plate, whereby when the locking-arm is carried to locking position the solid portion of the plate is over the projections from the retaining-arms, preventing 100 the movement of the said arms, and whereby when the locking-arm is in releasing position the openings in the plate register with the openings in the box-casing, to permit the movement of the retaining-arms away from 105 each other.

3. In mechanisms for supporting and locking articles to their supports, a main casing, a box-casing fitted to the main casing, being open at its front and provided with openings at its rear, spring-controlled retaining-arms pivoted in the said box-casing and adapted 115 for movement to and from each other, projections from the retaining-arms, extending into the openings in the back of the box-casing, a disk mounted to revolve in the main casing, provided with a keeper-section, means for turning the said disk in one direction, a spring attached to the disk and to the main casing, controlling the movement of the disk in an opposite direction, a locking device for the said disk, means for limiting the rotation of the disk in a direction away from the locking device when released therefrom, a plate mounted to slide over the back of the said 120

body-casing, having openings therein capable of registry with the back of the body-casing, and a connection between the plate and the disk, whereby the two simultaneously operate and the plate is carried either to a position for locking the said arms or to a position for releasing the said arms.

In testimony whereof I have signed my name to this specification in the presence of two subscribing witnesses.

JOHN CLETIOUS EPLER.
